UNITED STATES PATENT OFFICE

110,677

DESIGN FOR AN ELECTRIC GRILL OR THE LIKE

Howard A. Smith, St. Louis, Mo., assignor to Knapp-Monarch Company, St. Louis, Mo., a corporation of Missouri

Application November 29, 1937, Serial No. 73,244

Term of patent 7 years

To all whom it may concern:

Be it known that I, Howard A. Smith, a citizen of the United States and a resident in the city of St. Louis and State of Missouri, have invented a new, original, and ornamental Design, for an Electric Grill or the like, of which the following is a specification, reference being had to the accompanying drawing, forming part thereof.

Figure 1 is a perspective view of an electric grill or the like showing my new design.

and

Figure 3 is a top plan view thereof.

I claim:

The ornamental design for an electric grill or the like, substantially as shown.

HOWARD A. SMITH.
